UNITED STATES PATENT OFFICE.

JOHN CUBER AND ANTON HACKENBROCH, OF CHICAGO, ILLINOIS, ASSIGNEES
TO F. PATZACK MANUFACTURING COMPANY, A CORPORATION OF ILLINOIS.

DESIGN FOR A SEWING-MACHINE TABLE.

SPECIFICATION forming part of Design No. 35,486, dated December 24, 1901.

Application filed October 19, 1901. Serial No. 79,308. Term of patent 7 years.

To all whom it may concern:

Be it known that we, JOHN CUBER and ANTON HACKENBROCH, citizens of the United States, residing at Chicago, in the county of Cook and State of Illinois, have invented and produced a new and original Design for a Sewing-Machine Table, of which the following is a specification, reference being had to the accompanying drawings, forming a part hereof.

Figure 1 is a front elevation of a sewing-machine table embodying our new design. Fig. 2 is a top plan view of such sewing-machine table, and Fig. 3 is an end elevation of such table.

All of the figures given are necessary to properly show our new design.

A reference-letter applied to designate a given part is used to indicate such part throughout the several figures of the drawings wherever the same appears.

As shown in the drawings, the leading or material features of our design consist of the

top boards A, the table B, the portion of the front lettered C, C', and D, and the end portions of the front, which are lettered E E. The parts lettered C, C', and D have somewhat the relation to each other of an ordinary bay-window to a house, the parts D D being at an obtuse angle to the parts C C'. The parts E E are rounded at their ends.

Having thus described our invention, what we claim as new, and desire to secure by Letters Patent, is—

The design for a sewing-machine table as shown and described.

In testimony whereof we have signed our names to this specification in the presence of two subscribing witnesses.

JOHN CUBER.
ANTON HACKENBROCH.
